[57] CLAIM

The ornamental design for a beach accessory, as shown and described.

DESCRIPTION

FIG. 1 is a top front perspective view of a beach accessory showing my new design;

FIG. 2 shows my new design in the "tote" mode;

FIG. 3 is a top view of my new design; and,

FIG. 4 is a bottom perspective view thereof.

The broken lines are for environmental purposes only and form no part of the claimed design.
